DISPLAY CABINET FOR CIGARETTES AND THE LIKE

Edward L. Bayly, 639 La Loma Road City,
Pasadena, Calif.

Filed May 7, 1965, Ser. No. 85,176

Term of patent 14 years

(Cl. D80—11)

FIG. 1.

FIG. 2.

FIG. 3.

FIG. 4.

FIG. 1 is a front perspective view of a display cabinet for cigarettes and the like showing my new design;

FIG. 2 is an elevational view taken from the left side thereof;

FIG. 3 is an elevational view thereof; and

FIG. 4 is an elevational view taken from the right side thereof.

I claim:

The ornamental design for a display cabinet for cigarettes and the like, substantially as shown.
